UNITED STATES PATENT OFFICE.

FRED S. GIFFORD, OF NEW BEDFORD, MASSACHUSETTS, ASSIGNOR OF ONE-HALF TO ANSEL G. BAKER, OF SAME PLACE.

DISPLAYING-RECEPACLE.

SPECIFICATION forming part of Letters Patent No. 427,982, dated May 13, 1890.

Application filed October 10, 1889. Serial No. 326,576. (No model.)

To all whom it may concern:

Be it known that I, FRED S. GIFFORD, of New Bedford, in the county of Bristol and State of Massachusetts, have invented a new and useful Receptacle, of which the following is a specification, reference being had to the accompanying drawings, in which—

Figure 1 is a plan, and Fig. 2 a vertical central section, of one form of receptacle embodying my invention.

My invention is a display-receptacle and an improvement on the so-called "grocer's bin" described in Hawkins's patent, No. 399,197, dated March 5, 1889.

15 My display-receptacle is made up of an open-mouthed bin, a movable bottom, and means for raising and lowering that bottom, said means being interposed between the under surface of the movable bottom and a support secured to the walls of the bin.

In the drawings, *a* is an open-mouthed bin; *a'*, the movable bottom, which is preferably provided with a strip *a³* of rubber or leather around its margins, and so mounted that it 25 grazes the inner surfaces of the side walls of the bin when bottom *a'* is moved. The means for raising and lowering bottom *a'* are interposed between the under surface of bottom *a'* and a support *a³*, which is secured to the 30 walls of bin *a*. By this construction no part

of the raising and lowering device projects above the upper surface of bottom *a'*, and this is important, because a projection above the upper surface of the bottom seriously interferes with scooping out the contents of the bin. The means for raising and lowering the bottom *a'* are the male screw 1 and female screw 2, having a handle 3, the female screw 2 being secured at its lower end in a bearing 4 on support *a³*, and at its upper end 40 in a bearing 5, formed in cross-piece 6, secured to the walls of the bin. A female screw 1 is rigidly secured to bottom *a'*, and by turning female screw 2 bottom *a'* is raised or lowered, as desired. 45

What I claim is—

The herein-described displaying-receptacle, made up of an open-mouthed bin *a*, a movable bottom *a'*, support *a³*, provided with a bearing 4, cross-piece 6, provided with a bearing 5, male screw 1, supporting bottom *a'*, and female screw 2, provided with handle 3, the female screw 2 being supported in bearings 4 and 5, substantially as and for the purpose set forth. 50

FRED S. GIFFORD.
